UNITED STATES PATENT OFFICE.

JOHN HARRISON, OF PHILADELPHIA, PENNSYLVANIA.

HAND-GRIP FOR TELEPHONE-STANDARDS.

1,122,593.

Specification of Letters Patent.

Patented Dec. 29, 1914.

Application filed July 1, 1914. Serial No. 848,839.

To all whom it may concern:

Be it known that I, JOHN HARRISON, a citizen of the United States, residing at Philadelphia, in the county of Philadelphia and State of Pennsylvania, have invented certain new and useful Improvements in Hand-Grips for Telephone-Standards, of which the following is a specification.

My invention relates to improvements in hand grips for telephone standards, the object of the invention being to provide a grip of the character stated which can be readily positioned on any telephone standard, and which will prevent contact of the hand with the metal of the standard which will act as an insulator to prevent any possibility of the hand receiving an electric shock, and which will not disfigure the telephone or interfere with its ordinary functions.

20 A further object is to provide a grip of the character stated composed preferably of rubber or other non-conducting flexible or elastic material having springs embedded in the material and operating to clamp the grip around the standard, so that it can be readily placed in position or removed as desired.

With these and other objects in view, the invention consists in certain novel features 30 of construction and combinations and arrangements of parts as will be more fully hereinafter described and pointed out in the claims.

In the accompanying drawings: Figure 1 is a view in side elevation illustrating a desk telephone of the ordinary type provided with my improved grip. Fig. 2 is a view in cross section on the line 2—2 of Fig. 1 showing the spring embedded in the material 40 of the grip in elevation, and Fig. 3 is a perspective view illustrating the clamping springs in full lines and the grip in dotted lines.

My improved grip comprises a split cylinder 1 having at its lower end a split base 2. The base and the cylindrical casing conforming in shape to the base 3 and standard 4 of an ordinary telephone and having an offset portion 5 at the juncture of the casing and the base to conform in shape to the ordinary telephone.

As above stated, the casing 1 of the base 2, is split, and at the split portion, the base 2 is recessed as shown at 6 to accommodate the wires 7 which extend into the base 3 of the telephone standard.

Within the material of casing 1, I embed springs 8. These springs are composed preferably of strips of spring metal, circular in form with their ends terminating short of the edges of the casing at the split therein, so that in positioning the grip around the standard 4, the casing and the base portion 2 can be opened at the split sufficiently to allow the same to receive the standard, and when the standard is in place and the grip released, the springs 8 will tightly bind the grip around the outside of the standard and hold the same in place.

The grip is preferably of rubber, although I may use other flexible resilient and non-conducting material. The springs 8 are molded in the material of the grip, and are inclosed in said material, so that they do not contact with the standard of the telephone, yet give to the grip the necessary elasticity to tightly hold the same upon the standard.

When in use, the operator grasps the grip and his hand is entirely insulated from the standard and protected from any metal of the standard which might be injurious to him. As the base portion 2 of the grip extends over the base 3 of the telephone standard, the hand is protected from the metal of the base as well as from the metal of the standard and in fact, the grip operates as an efficient protection against injury to the hand either by electric shocks or by reason of contact with metal of some sort.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A grip of the character stated, comprising a cylindrical split casing of elastic material adapted to be sprung to position around the standard of a telephone, said casing at one end having a flared base portion adapted to be positioned over and cover the upper portion of the base of the telephone, substantially as described.

2. A grip of the character stated, comprising a cylindrical casing and base composed of flexible non-conducting material, said casing and base split throughout their

length, said cylindrical portion of the casing adapted to inclose the standard of a telephone, and said split base adapted to cover the base of a telephone, and springs spaced apart and embedded in the material of the casing with the ends of the springs terminating short of the edges of the casing at its split, substantially as described.

Copies of this patent may be obtained for five cents each, by addressing the "Commissioner of Patents, Washington, D. C."

In testimony whereof I have signed my name to this specification in the presence of two subscribing witnesses.

JOHN HARRISON.
